UNITED STATES PATENT OFFICE.

SAMUEL BRETZFIELD, OF NEW YORK, N. Y.

DESIGN FOR A TOY BANK.

SPECIFICATION forming part of Design No. 20,375, dated December 9, 1890.

Application filed October 17, 1890. Serial No. 368,494. Term of patent 3½ years.

To all whom it may concern:

Be it known that I, SAMUEL BRETZFIELD, of the city of New York, in the county and State of New York, a citizen of the United States, have invented a certain new Design for Toy Banks, of which the following is a specification.

In the accompanying drawing a perspective view of my improved design for toy banks is shown.

The leading feature of my design consists in the coin-receptacle made in the form of a horn.

A is a coin-receptacle having the shape of a horn.

B is the coin-slot.

C is the gate at the larger end of the receptacle; D, the lock; E, an ornamental end band; F, the ornamental tip; G, a chain, and

H a loop.

Having thus described my design, I claim as new and desire to secure by Letters Patent—

The design herein shown and described for a toy bank, consisting of a receptacle having the shape of a horn, an ornamental band at the larger end, an end plate across said larger end, a tip at the smaller end, and a slot between the two ends, substantially as set forth.

In testimony that I claim the foregoing as my invention I have signed my name in presence of two subscribing witnesses.

SAML. BRETZFIELD.
